(57) **CLAIM**

The ornamental design for a welding hood, as shown and described.

DESCRIPTION

FIG. 1 is an upper left front perspective view of a welding hood showing my new design in accordance with a first embodiment of the present invention;

FIG. 2 is an upper rear right perspective view thereof;

FIG. 3 is a top view thereof;

FIG. 4 is a bottom view thereof;

FIG. 5 is a right side elevation view thereof;

FIG. 6 is a left side elevation view thereof;

FIG. 7 is a front elevation view thereof;

FIG. 8 is a rear elevation view thereof;

FIG. 9 is an upper right front perspective view of a welding hood showing my new design in accordance with a second embodiment of the present invention;

FIG. 10 is an upper right rear perspective view thereof;

FIG. 11 is a top view thereof;

FIG. 12 is a bottom view thereof;

FIG. 13 is a right side elevation view thereof;

FIG. 14 is a left side elevation view thereof;

FIG. 15 is a front elevation view thereof in an optional condition of use; and,

FIG. 16 is a right side elevation view thereof in an optional condition of use.

The portions of the welding hood shown in broken lines form no part of the claimed design.
